G. A. BUTTRESS:
DRYING, CURING, AND SHAPING ROLLS FOR WALL BOARD.
FILED SEPT. 15, 1921.

2 SHEETS-SHEET 2

UNITED STATES PATENT OFFICE.

GEORGE A. BUTTRESS, OF LOS ANGELES, CALIFORNIA, ASSIGNOR TO BUTTRESS MANUFACTURING COMPANY, A CORPORATION OF CALIFORNIA.

DRYING, CURING, AND SHAPING ROLLS FOR WALL BOARD.

Application filed September 15, 1921. Serial No. 500,809.

To all whom it may concern:

Be it known that I, GEORGE A. BUTTRESS, a citizen of the United States, residing at Los Angeles, in the county of Los Angeles and State of California, have invented new and useful Improvements in Drying, Curing, and Shaping Rolls for Wall Board, of which the following is a specification.

My invention relates to an apparatus for drying, curing and shaping wall or plaster board or like material that is formed in continuous sheets, the principal objects of my invention being to provide a relatively simple, practical and easily operated apparatus that may be economically employed in the treatment of newly formed plaster board and the like, and further to provide an apparatus of the character referred to that will be very effective in rapidly drying and curing wall or plaster board and imparting thereto, smooth finished surfaces.

With the foregoing and other objects in view my invention consists in certain novel features of construction and arrangement of parts that will be hereinafter more fully described and claimed, and illustrated in the accompanying drawings, in which:

Figure 1 is a plan view of a wall or plaster board conveyor, and showing a drying and finishing apparatus of my improved construction associated therewith.

Figure 2 is an enlarged cross section taken on the line 2—2 of Figure 1.

Figure 3 is a side elevational view of my improved apparatus with a portion of the housing broken away.

Referring by numerals to the accompanying drawings, 10 designate aligned endless conveyors that operate on suitably journaled drums or rollers 11, and which are utilized for handling elongated or practically continuous sections of wall or plaster board B.

Arranged between the adjacent ends of the conveyors 10 and supported on a suitable framework 12 is the apparatus contemplated by my invention, and which includes a substantially rectangular box or housing 13, preferably formed of metal and provided in its top with a heated air outlet pipe 14.

The end walls of the box or housing 13 are provided with openings 15 which permit the passage of the wall or plaster board B lengthwise through the housing.

Arranged between the open ends of the 55 housing and the drums or rollers 11 are supporting brackets 16 having inclined top surfaces and adjustably arranged upon the latter are journal blocks 17 for the trunnions of wall or plaster board supporting 60 rollers 18. These vertically adjustable rollers 18 together with similar rollers hereinafter described, provide means for determining the horizontal plane that is occupied by that portion of the wall or plaster 65 board that is positioned between the endless conveyors 10.

Arranged on support 12 at the center of housing 13 is a transversely disposed box-like member 19 having a smooth top surface 70 over which the wall or plaster board is adapted to pass, and projecting upwardly from the ends of this box are brackets 20 that serve to support a transversely disposed tube 21, the rear end of which is closed by a 75 plug 22.

Mounted to rotate freely upon tube 21 is a relatively heavy hollow roller 23, having openings 24 in its ends, and formed in the tube within said roller are apertures 25. 80 The periphery of roller 23 is spaced a pre-determined distance above the smooth top surface of box 19 and this distance is equal to the finished thickness of the wall or plaster board.

Arranged for vertical adjustment on the sides of the box are brackets 26 in which are journaled shafts 27 and the latter carrying rollers 28 that co-operate with the rollers 18 in supporting the wall or plaster 90 board in its passage through the apparatus.

Extending lengthwise through box 19 is a tube 29 closed at its rear end, and said tube within said box being provided with apertures 30. Projecting upwardly from the sides of support 12 between the box 19 and one of the end walls of the housing 13 are brackets 31 that support a box 32 having a smooth under surface and against which the upper face of the wall or plaster board is adapted to engage during its movement through the apparatus. Extending lengthwise through box 32 is a tube 33 that is a counterpart of tube 29, said tube 33 being closed at its rear end and perforated 100 within the box.

Extending through the lower portions of brackets 31 is a transversely disposed tube

34 that is a counterpart of tube 21, and arranged to rotate freely upon said tube is a hollow roller 35 the periphery of which is spaced a predetermined distance from the underside of box 32. The rear end of tube 34 is closed and it is perforated within the hollow roller 35.

Projecting upwardly from support 12 between box 19 and the end of housing 13 having the opening through which the wall or plaster board enters the apparatus are standards 36 through the upper and lower portions of which pass tubes 37 that are counterparts of the tubes 29 and 34.

15 Arranged to rotate freely upon these tubes are hollow rollers 38 that are counterparts of the rollers 23 and 35. These rollers are spaced a predetermined distance apart and in operation their peripheries are adapted to make direct contact with the upper and lower surfaces of the wall or plaster board passing through the apparatus. The rear ends of the tubes 37 are closed and said tubes, within the rollers, are perforated.

25 Connected to the forward ends of the tubes 21, 29, 33, 34 and 37 are housings 39 provided in their outer walls with openings that are adapted to be closed by dampers 40 and connected to each housing 39 is a 30 valve 41. Connected to all of the valves 41 are branch pipes 42 that lead from a main pipe 43, and which latter leads from a suitable source of steam or heated air supply.

In operation the wall or plaster board is 35 carried through the apparatus by the endless carriers 10, and in passing from one carrier to the other the board passed between rollers 38, over the smoothed top surface of box 19 and beneath roller 23, and beneath the 40 smoothed under surface of box 32 and over roller 35. The boxes and rollers are heated to the proper degree by the admission of steam or heated air to the chambers within said boxes and rollers, from the perforated 45 tubes 21, 29, 33, 34 and 37 and which latter receive steam or heated air from the branch pipes 42 that are connected to main supply pipe 43.

Thus both surfaces of the wall or plaster 50 board are directly engaged by the heated boxes and rollers, with the result that said board will be very quickly dried and cured and at the same time said board will be pressed to the proper thickness and both 55 surfaces of the board will be smoothed and finished in the desired manner. The finishing and drying rollers 23, 35 and 38 rotate as a result of their frictional engagement with the wall or plaster board during 60 its travel through the machine. The adjustable rollers 18 and 28 co-operate with each other and with the drying and finishing rollers and boxes in supporting the board while passing through the apparatus and 65 the amount of steam or heated air admitted

to the rollers and boxes may be very accurately controlled by proper manipulation of the various valves 41.

Thus it will be seen that I have provided a simple, practical and efficient drying, cur- 70 ing and finishing apparatus for wall or plaster board and like products.

It will be understood that minor changes in the size, form and construction of the various parts of my improved apparatus 75 may be made and substituted for those herein shown and described without departing from the spirit of my invention, the scope of which is set forth in the appended claims.

I claim:

1. In an apparatus for drying and finish- 80 ing wall and plaster board, the combination with a pair of endless conveyors, of a housing arranged between said conveyors, a pair of finishing rollers journaled for rotation within said housing, and means for heating said rollers.

2. In an apparatus for drying and finish- 85 ing wall and plaster board, the combination with a pair of endless conveyors, of a housing arranged between said conveyors, a box within said housing, a roller arranged for operation within said housing adjacent to said box, and means for heating said box and roller.

3. In an apparatus for drying and finish- 90 ing wall and plaster board, a housing through which the board is adapted to pass, rollers for supporting the board during its passages through the housing, and a pair of heated drying and finishing rollers arranged for operation within the housing and between which the board is adapted to pass.

4. In an apparatus for drying and finish- 95 ing wall and plaster board, a housing 100 through which the board is adapted to pass, rollers for supporting the board during its passages through the housing, and a heating box and heating roller arranged within the housing and spaced apart to receive the 110 wall of plaster board.

5. In an apparatus for drying and finish- 115 ing wall or plaster board, a housing, a heating box arranged therein and provided with a smooth finishing surface, a heated roller 120 arranged for operation within said housing adjacent to the finishing surface of the roller, and means for moving wall or plaster board between said box and roller.

6. In an apparatus for drying and finish- 120 ing wall or plaster board, a housing, a pluri- 125 ality of pairs of co-operating heating and finishing members within said housing, and means for moving wall or plaster board between said heating and finishing members.

7. In an apparatus for drying and finish- 130 ing wall or plaster board, a housing, a pluri- 135 ality of pairs of co-operating heating and finishing members within said housing cer- 140 tain of which members are relatively sta-

tionary, and means for moving wall or plaster board between said heating and finishing members.

8. In an apparatus for drying and finishing wall or plaster board, a housing, a plurality of pairs of co-operating heating and finishing members within said housing certain of which members are rotatively mounted, and means for moving wall or plaster board between said heating and finishing members.

9. In an apparatus for drying and finishing wall and plaster board, a housing, a series of pairs of co-operating heating and finishing members arranged with said housing certain of which members are stationary and other members being rotatively mounted, and means for uniformly heating all of said members.

10. In an apparatus for drying and finishing wall and plaster board, a housing, a series of pairs of co-operating heating and finishing members arranged with said hous-

ing certain of which members are stationary and other members being rotatively mounted, means for uniformly heating all of said members, and means for moving wall or plaster board between said heating and finishing members.

11. In an apparatus for drying and finishing wall board, the combination with means for imparting movement to a sheet of wall board and combined heating and finishing rollers between which the sheet of wall board is adapted to pass and which rollers are rotated by frictional contact with said wall board.

12. In an apparatus for drying and finishing wall board, a housing combined heating and finishing rollers arranged for operation within said housing and means for moving a sheet of wall board between said rollers so as to cause the same to rotate as a result of frictional contact with said rollers.

GEORGE A. BUTTRESS.
